UNITED STATES PATENT OFFICE.

ALFRED P. LOHMAN, OF AKRON, OHIO

ANCHORING DEVICE FOR USE IN CONNECTION WITH CONCRETE STRUCTURES.

1,090,486.

Specification of Letters Patent. Patented Mar. 17, 1914.

Application filed October 2, 1911, Serial No. 652,231. Renewed November 6, 1913. Serial No. 799,626.

To all whom it may concern:

Be it known that I, ALFRED P. LOHMAN, a citizen of the United States, residing at Akron, in the county of Summit and State of Ohio, have invented new and useful Improvements in Anchoring Devices for Use in Connection with Concrete Structures, of which the following is a specification.

This invention relates to devices for holding or supporting articles such as hangers, shafting, sprinkler-pipes, and the like, in buildings composed of self-hardening plastic material such as concrete, and is of the same general type as the device shown in the patent granted to me March 1, 1910, No. 950,771.

The object of this invention is to provide a holder or support, preferably of metal, adapted to be suitably positioned and embedded in the plastic material of which the building is composed so that when the material becomes set the device will be securely anchored therein.

More specifically, the invention contemplates the provision of a member adapted to be embedded in the cementitious material of a building and provided with a recess, the length of which is greater than its width so as to permit adjustment of the position of the coupling-member which is located therein and supported by the walls of the recess. As shown in the patent before mentioned, the walls of the recess are inclined toward each other to constitute a wedge-shaped abutment on which is adapted to be seated a coupling-member provided with a recess to receive a nut on the threaded end of a bolt, said coupling-member provided with diametrical opposite side faces arranged to engage the inclined walls of the recess, whereby said coupling-member is wedged between said walls when supporting an object and at the same time, the nut on the bolt is suitably seated in the recess in the coupling-member.

A further object of the invention is to form in the side walls of the device one or more notches communicating with the recess and into which the bolt or suspension-device carried by the coupling-member may be swung laterally to permit the insertion and removal of the coupling-member without detaching the bolt therefrom.

With the foregoing and other objects in view, the invention consists in the novel construction, combination and arrangement of

parts constituting the invention to be herein-after specifically described and illustrated in the accompanying drawings which form a part hereof wherein is shown the preferred embodiment of the invention, but it is to be understood that changes, variations and modifications can be resorted to which come within the scope of the claims hereunto appended.

In the drawings in which similar reference numerals indicate like parts in the different figures; Figure 1, is an end elevation of a device embodying this invention; Fig. 2, is a side elevation of the device shown in Fig. 1; Fig. 3, is a transverse central sectional view on line X of Fig. 2 showing the device mounted in a cementitious structure and the coupling-member positioned in operative relation therewith; Fig. 4, is a view similar to Fig. 3 showing the position of the parts during the insertion and removal of the coupling-member; and, Fig. 5, is a plan of the coupling-member detached.

The body-portion of the device comprises a member 1 preferably having a rounded upper surface at the point 2 and a flat base 3 and containing a recess 4 provided with a contracted outlet 5 formed by the inwardly-inclined side walls 6 which form when associated together a wedge-shaped abutment. Extending transversely from the lateral faces of the body-portion 1 are a pair of oppositely disposed lugs 7 on opposite sides of which are smaller lugs 8 so as to form between the lugs 7 and 8 notches 9 for a purpose to be later described. Communicating with the recess 4 and usually provided within the body-portion of the lugs 7 are notches 10 outwardly-flaring from the recess 4. The upper face or wall 2 of the device is provided with an upwardly-extending inverted bell-shaped integral member 11 preferably containing a recess 12 for a purpose to be later described.

Mounted on the inclined faces 6 of the recess 4 and which constitute a wedge-shaped abutment therefor is a coupling-member 13 having inclined side faces shaped to engage the inclined faces 6 of the recess and with the ends thereof approximately vertically-formed. The coupling-member 13 is provided with a central aperture 14 and with a recess 15 surrounding said opening and preferably square to constitute a seat for a purpose to be later described. The coupling-

member 13 is further preferably provided with a recess 16 larger than the recess 15 and connected with the latter by a shoulder 17, the latter recess being shallower than the recess 15. The recesses 15 and 16 in the coupling-member 13 are adapted to constitute seats for different sizes of nuts 18 which are mounted therein and which, of course, are provided with centrally-threaded orifices to receive the threaded ends 19 of hanger-bolts 20.

The device is adapted to be mounted in a cementitious wall with its lower recessed face approximately flush with the face of said wall and with its upper bell-shaped portion 11 entirely embedded in the structure so as to firmly anchor the device against movement. This is usually accomplished by placing the support on a temporary wooden floor of the form used for making the cementitious wall and temporarily holding it in position by hold-fast devices passed through the notches 9 existing between the lugs 7 and 8, after which the soft plastic cementitious material is placed in the form and completely incloses the device so as to support the latter when the plastic material becomes hard or solid. Afterward the floor of the form is removed leaving the device embedded in the wall approximately as shown in Figs. 3 and 4.

The parts are assembled as follows: A nut of suitable size is placed on one of the seats formed by either of the recesses 15 or 16, and the threaded end of the bolt passed upwardly through the opening 14 which is of sufficient diameter to clear the threads on the bolt and the coupling-member 13 is inserted in the recess. In doing this, the bolt 20 is swung laterally into one of the notches 10 which are provided for this purpose, that is to say, are so formed and positioned as to permit the tilting of the bolt sufficiently to enable the operator to insert the coupling-member 13 in the recess 4. As these notches 10 are provided at one point only in the side

walls of the member 1 it is necessary to shift the position of the coupling-member 13 to a point opposite to one of the notches 10 in order to permit the withdrawal of the same. When the coupling-member has been positioned with its inclined side faces resting against the inclined side faces 6 of the recess and which constitute a wedge-shaped abutment for this purpose, the bolt may then be revolved to force its threaded upper end against the roof or upper wall of the recess 4 and by the pressure exerted by the engagement between the nut 18 and the threads on the bolt, the coupling-member 13 is securely clamped against longitudinal shifting, and it will be apparent that if it is desired to remove the member, the bolt 20 must be unscrewed sufficiently to permit it to be tilted in the manner shown in Fig. 4 which permits its ready withdrawal through the opening formed in the outlet of the recess 4.

I claim:

An anchoring device for the purpose set forth comprising a body-portion having a recess formed in the lower portion thereof and provided with side walls inclined inward toward the lower face thereof to constitute a wedge-shaped abutment, each of said side walls being provided with centrally-disposed lateral extensions arranged to form recesses communicating with the first-mentioned recess and inclined at angles thereto; in combination with a coupling member adapted to be inserted in and fit said first-mentioned recess, said coupling member being arranged to pass through a selected one of the last-mentioned recesses in entering the first recess.

In testimony whereof I have hereunto set my hand in presence of two subscribing witnesses.

ALFRED P. LOHMANN.
